UNITED STATES PATENT OFFICE.

PHILIP LINDEMEYR, OF BALTIMORE, MARYLAND, ASSIGNOR TO THE AMERICAN STOPPER COMPANY, OF NEW YORK, N. Y.

DESIGN FOR A VESSEL-CAP.

SPECIFICATION forming part of Design No. 30,766, dated May 16, 1899.

Application filed April 18, 1899. Serial No. 713,513. Term of patent 7 years.

To all whom it may concern:

Be it known that I, PHILIP LINDEMEYR, of the city of Baltimore and State of Maryland, have invented and produced a new and original Design for Caps for Closing Vessels, of which the following is a specification, reference being had to the accompanying drawings, forming part thereof.

Figure 1 is a perspective of a cap, showing my new design. Fig. 2 is a vertical central section of the same.

The leading feature of my design consists in the corrugations 3 of the cap-flange 1, having plain faces 2, intermediate groups of corrugations 3, and provided with depressions 4.

The corrugations extend near to the rounded portion 5 at the upper end of the cap, which has a centrally-situated depressed portion 6. 7 indicates depressions formed in the rounded portion 5. 20

Having described my invention, what I claim as new, and desire to secure by Letters Patent, is—

The design for a vessel-cap, as herein shown and described.

PHILIP LINDEMEYR.
